(57) **CLAIM**

The ornamental design for a basketball system front cover, substantially as shown and described.

DESCRIPTION

FIG. 1 is a front perspective view of a basketball system front cover in accordance with the present invention;

FIG. 2 is a front perspective view in an alternate use state thereof;

FIG. 3 is another front perspective view in an alternate use state thereof;

FIG. 4 is a side elevation view thereof;

FIG. 5 is another side elevation view thereof;

FIG. 6 is a front elevation view thereof;

FIG. 7 is a rear elevation view thereof; and,

FIG. 8 is a top plan view thereof.

The broken lines showing the basket, support structure, and the base in the drawings depict environment only and form no part of the claim, while all other broken lines depict portions of the basketball system front cover that form no part of the claimed design.

1 Claim, 8 Drawing Sheets
